UNITED STATES PATENT OFFICE.

RUSSEL G. WOODWARD, OF WAUKEGAN, ASSIGNOR TO THE UNION SPECIAL SEWING MACHINE COMPANY, OF CHICAGO, ILLINOIS.

THREAD-CONTROLLING DEVICE FOR SEWING-MACHINES.

SPECIFICATION forming part of Letters Patent No. 427,026, dated April 29, 1890.

Application filed March 30, 1889. Serial No. 305,362. (No model.)

To all whom it may concern:

Be it known that I, RUSSEL G. WOODWARD, of Waukegan, county of Lake, State of Illinois, have invented an Improvement in Take-Up for Sewing-Machines, of which the following description, in connection with the accompanying drawings, is a specification, like letters on the drawings representing like parts.

This invention has for its object to provide a sewing-machine with a thread-controller which shall have its position varied automatically to provide for variations in thickness of the cloth or other material under the presser-foot, and thus give to the needle and stitch-forming devices sufficient slack thread to accord with the thickness of the material.

In this invention the presser-bar has an attached rack which rises and falls in unison with it, the teeth of the said rack engaging with teeth at the end of a thread-controlling lever, having a long arm which is extended from its fulcrum backwardly toward the tension device, where it is provided with an eye to receive the thread.

To make the thread-controlling lever light, so that but little power is required to move it, the said lever has been constructed of a plate and a wire.

My invention consists, essentially, in the combination, with the work-support, presser-foot, presser-bar, and rack attached thereto and rising and falling with the presser-bar, of a thread-controlling lever having teeth at one end and an eye at the other end, and it being adapted to act upon the thread on its way to the eye of the needle and cause more slack thread to be given to the needle as the thickness of the material under the presser-foot varies, and vice versa.

Figure 1 in side elevation represents a sufficient portion of a sewing-machine to enable my invention to be understood, the needle-bar being partially broken out to show the presser-bar and rack attached thereto behind it, the thread-controlling lever being shown by dotted lines in the position it would occupy if the thickness of the material should be increased, as shown by dotted lines under the presser-foot; and Fig. 2 is a detail to be referred to.

The bed-plate A, the overhanging arm A',

containing the usual bearings for the needle and presser bars, the needle-actuating arm B, the link B', connected to a block secured to the needle-bar B², are partially broken out in Fig. 1. The said needle-bar and the presser-bar C and presser-foot C² are and may be all of usual construction. The presser-bar C has applied to it the collar C³, forming part of the rack C', having teeth 2, the said hub having a projection c, the collar being held in adjusted position on the presser-bar by a setscrew c'. The pin or projection c is in practice acted upon by a suitable strong spring c², attached at its opposite end to the overhanging arm A', the said spring normally acting to keep the presser-foot down upon the material under it. The spring c² is of common use in sewing-machines.

The overhanging arm A' has a stud-screw D', which constitutes the fulcrum for the thread-controlling lever D, having at one end a series of teeth 3, to be engaged by the teeth 2 of the rack C', which, as described, is connected to and rises and falls in unison with the presser-bar, according to the thickness of the material under the presser-foot.

The lever D, to make it light and yet sufficiently stiff, has a part of it composed of wire, as at 4, the said wire being bent at its outer end to form a socket for the reception of a stud-screw 5, to secure to the end of the thread-controller the eye 6, through which the needle-thread t is passed after leaving the usual tension device t², the said needle-thread being represented as carried through an ordinary loop or eye b at the upper end of the needle-bar, and thence through the eye of the usual eye-pointed needle.

The tension device may and in practice will be substantially the same as in United States Patent No. 344,493, dated June 29, 1886.

In operation, as the material varies in thickness—say, for instance, as the material increases in thickness—the presser-foot rises and causes the eye 6 to descend, as represented by dotted lines, and effect the production of more slack in the needle-thread, so that when the needle descends more slack will be given up to the formation of the stitch than when the material under the presser-foot is thinner. By extending the lever D well back

toward the tension device a slight movement of the presser-bar gives considerable movement to the lever between the tension device and its point of support on the needle-bar.

5 I claim—

1. The combination, with the work-support, needle-bar, presser-foot, presser-bar, rack-plate connected to and rising and falling with the presser-bar, and a tension device, of the pivoted thread-controlling lever having teeth engaged by the said rack and extended horizontally toward the tension device and acting on the needle-thread between the tension device and needle-bar, to operate substantially as described.
- 5 2. The presser-bar, its attached toothed

rack, and the tension device combined with the overhanging arm, and the thread-controlling lever D, pivoted thereon and extended back toward the said tension device, the said 20 thread-controlling lever having teeth 3 at one end, and having one of its arms composed of wire-like material, as at 4, to operate substantially as described.

In testimony whereof I have signed my 25 name to this specification in the presence of two subscribing witnesses.

RUSSEL G. WOODWARD.
